United States Patent Office.

CHARLES J. WOOLSON, OF CLEVELAND, OHIO.

Design No. 3,080, dated June 30, 1868.

DESIGN FOR THE DOORS OF A COOK'S STOVE.

The Schedule referred to in these Letters Patent and making part of the same.

TO WHOM IT MAY CONCERN:

Be it known that I, CHARLES J. WOOLSON, of Cleveland, Ohio, have originated and designed a new style and configuration of Ornament for Cooking-Stoves, including the doors and legs; and I hereby declare that the following is a full and exact description thereof, reference being had to the accompanying drawing, in which my ornamental design is clearly represented.

The ornament upon the doors consists of a border of oval-shaped bead-work, and is seen at A A A A in the printed drawing.

In the centre of the large door are the head and bust of a man in armor, as seen at B. On each of the smaller doors is a mailed head, as seen at C C in the drawing. On the front doors, in the centre, is a shield, surmounted by a mailed head, with a bird in the act of alighting thereon, as seen at D D. A mailed head is also seen on the leg at E.

What I claim as my invention, and desire to secure by Letters Patent, is—

The ornamental configuration and design for cooking-stoves, as herein described, and shown in the drawing by letters of reference to the different portions thereof.

CHARLES J. WOOLSON.
